UNITED STATES PATENT OFFICE.

HARRY WISE RICHARDS, OF BALTIMORE, MARYLAND.

AUTOMATIC SAFETY RAILWAY SYSTEM.

1,268,879.

Specification of Letters Patent. Patented June 11, 1918.

Application filed September 2, 1916. Serial No. 118,249.

To all whom it may concern:

Be it known that I, HARRY WISE RICHARDS, residing at Baltimore, State of Maryland, have invented a new and useful Automatic Safety Railway System, of which the following is a specification.

The objects of my invention are, first, to prevent collisions on railroads; second, to prevent wrecks caused by broken or spread rails; third, to avoid depending upon the thoughtfulness and activity of a human being.

I attain these objects by the mechanism illustrated in the accompanying drawings, 15 in which—

Figure 1 shows the track arrangement; Fig. 2 shows plan and side elevation of stop rails shown at "5" Fig. 1; Fig. 3 shows second set of rails shown at "6" Fig. 1; 20 Fig. 4 shows the construction of these rails; Fig. 5 shows the wire connections of the engine; Fig. 6 shows construction of insulating joint shown at "1" and "2" Fig. 1; Fig. 7 shows construction of switch box placed under engine is at "40" Fig. 8; Fig. 25 8 shows location and arrangement of engine apparatus; Fig. 9 shows attachment to rail that will cause a "spread rail" to short circuit the track battery and cause a stop effect; Fig. 10 shows attachment to throttle; Fig. 11 shows plan and end view of apparatus to close throttle, as at "42" Fig. 8; and Fig. 12 shows construction of valve box and light as shown at "41" Fig. 8.

35 The roadway apparatus is shown in Fig. 1, in which "1" and "2" are insulating joints. The battery "4" is connected at the end of the block at "2", while two sets of rails "5" and "6" and the resistance "3" 40 are connected to the entrance of the block at "1". The arrow shows the direction of traffic. The stop rail "5" is placed far enough back of the rail "6" so when stop is effected by the "5" rail, the train will come to a 45 stop before reaching the entrance of the block at "1". The construction of this rail is shown in Figs. 2 and 4. Two rails running parallel with each other, "15" and "16" Fig. 4 are lag screwed to the scantling "17" which is the full length of the rails "15" and "16". The scantling "17" is lag 50 screwed to the blocks "18" which give the rails the proper level.

Fig. 2 shows plan and side view of stop 55 rail. The portion of the rail from "7" to "8" is about two inches higher than track. Be-

tween "8" and "9" is a rise of an additional two inches. From "9" to "10" is therefore about four inches higher than track. From "10" to "11" there is a drop 60 of two inches, back to the level of "7" to "8". "11" and "12" are on same level as from "7" to "8".

The rail "6" is placed just outside the entrance of the block at "1", Fig. 1. The construction is similar to the stop rail "5", the difference being that from "13" to "14" Fig. 3, is on a level about two inches above track, and has no high portion as in Fig. 2.

A train on the track anywhere between "1" and "2" short-circuits battery "4" and 65 prevents current from flowing through rails "5" and "6", causing a stop to be effected of another train on reaching the "5" rail. When the train comes to a stop the engineer must reset his apparatus and then run slowly until he reaches the "6" rail, where he must stop and wait until light gives him signal to "proceed". If when a train reaches the "5" rail the block is "clear", 70 current will be flowing in the "5" rail and no stop will be effected.

The resistance "3" is simply a few turns of wire around an iron core, the object of which is to complete the circuit of battery 75 "4" without short-circuiting it.

An insulating joint in the rail is shown in Fig. 6. These joints are placed in the rail to prevent current of one block flowing into another. A small space "25" is left between the ends of the rails so they do not touch. A piece of insulating material "26" the full length of the joint is fitted to each side of the rails. Iron castings "27" and "28" are placed on each side of the 80 ends of the rails, and castings attached to ends of one rail do not touch the castings on end of other rail. Bolts hold insulating material and castings firmly to rail. An iron plate "29" is placed under each end of 85 castings and joins castings on one side of rail with one on the other. Bolts or spikes pass through casting and plate into the tie.

If there is a break in a rail between "1" and "2" Fig. 1, the battery circuit is broken 90 and there will be no current in the stop rail and a stop will be effected.

A device for detecting a spread rail is shown at Fig. 9. It consists of a casting "43" which is cast into a point at "44", 95 spiked or bolted to the tie. This casting is connected by a wire "45" to the rail oppo-

site. If the rail should spread more than the distance allowed it will press against the point "44" and cause a short-circuit of the track, and a stop will be effected at the "5" rail.

5 The arrangement of the engine equipment is shown in Fig. 8. It consists of the switch box with contact rods "40", the valve box and light signal "41" and the throttle attachment "42".

10 The switch box is placed under the engine and the rods adjusted so contact shoes on end of the contact rods will hang about $1\frac{1}{2}$ inches above track level. The construction of a switch box is shown in Fig. 7. It consists of two contact rods with two contact shoes "30" and "31" attached to the ends, which are similar but work independent of each other. Attached to the top of the contact rod is the lever "38", which carries the spring brass contact piece "32" on a block of insulating material. The contact piece "32" is insulated from the lever "38", and a binding post "36" is attached to the spring 15 piece to make connections. The other lever "38" carries a similar contact piece "33". On the front of a block of insulating material "35" is fastened a brass plate "34". Both contact pieces "32" and "33" rest on plate "34" when contact rods are down. The binding post "37" is attached to the lever "38" to make connections. The length 20 of the contact springs "32" and "33" is such that upon a rise of $1\frac{1}{2}$ inches or more they will be off plate "34" and the circuit between them will be broken. A short link "39" is placed between the lever "38" and the standard to enable the contact rods to move in a vertical line.

25 30 35 40 A throttle attachment is shown in Figs. 10 and 11. Bolted to the throttle arm is the casting "46". Through a hole in casting "46" turns a rod, on the top end of which is fastened the lever "47", on the other end the lever "48", the levers "47" and "48" forming a bell crank. A pin "49" is placed 45 in the rod "51" which disengages throttle lock when raised. When rod "50" is pulled it causes lever "47" to move lever "48" which in turn raises rod "51" by pressing 50 against pin "49". When lever "47" is pulled as far as the lug "52" on casting "46" it can move lever "48" no farther, and the continuance of the pull draws the unlocked throttle 55 closed.

The pull necessary to close the throttle may be gotten by means of a cylinder containing a piston "54" Fig. 11. When compressed air enters at "53", piston "54" 60 pushes over lever "55", which in turn pulls rod "50". The other end of this rod "50" is attached to the end of lever "47" on throttle in Fig. 10. The short link "56" is to allow the piston to move in a straight line. 65 A valve box and signal light are shown

partly in section in Fig. 12. It consists of the valves "B" and "C" which are controlled by the electro-magnet "A". The valve "B" operates the braking system of the train, the valve "C" the throttle apparatus. Casting "D" contains two air chambers "63" and "65", and the piston "66" which operates the exhaust port "67". Attached to the handle "E" is a rod carrying on its upper end a disk "73". The raising of the handle "E" does two things; in case of an emergency, the engineer may set the brakes hard by raising the handle "E" which operates the exhaust cock "F"; the raising of the handle "E" also raises the lever "72" up to the magnet and resets the apparatus. The drawing shows the apparatus in the "set" position. Compressed air enters at "57" from the main reservoir (90 lbs.) passes through air strainer "G" 75 through pipes to valves "B" and "C". At valve "B" the air passes through the hole in casting, around groove "59" in piston, through other hole in casting, into chamber "63". The train line pressure (70 lbs.) 80 enters at "64" and passes into chamber "65". The pressure in the chamber "63" being greater than that in "65" holds piston down and keeps exhaust port "67" closed. The air from "57" cannot pass valve "C" as the solid 85 portion of the piston is between the holes in the casting. When the circuit is broken on magnet "A", lever "72", assisted by spring "71", falls and rests on top of disk "73". In doing so, the lever "72" causes the 90 other levers attached to it to release valve "B" and raises piston in valve "C". When the valve "B" is released, the spring "58" pushes piston out. The solid portion "60" 95 then comes between the holes in the casting and cuts off air supply to chamber "63". As the piston moves back, the point on end of piston moves out of exhaust port "62", and the air that is in chamber "63" then escapes through the groove "61" cut in casting, and 100 out port "62". When the air pressure in chamber "63" falls below that of "65", the piston "66" raises and opens port "67", which applies the air-brakes. When the piston in valve "C" is raised, the grooved 105 portion "68" has come between the holes in the casting and allows air from "57" to pass through pipe "53" to the cylinder in Fig. 11, which closes the throttle.

Raising handle "E" causes "73" to raise 110 and lifts "72" to magnet and returns apparatus to original position. When reset, the piston in valve "C" cuts off air supply to throttle cylinder, and the air that is in the cylinder escapes through groove "69" in 115 casting, out exhaust port "70". The brakes can then be released and the throttle opened in the usual manner.

A light signal is shown at "H", Fig. 12. A small box is constructed with a hole in it, 120

125

behind which is a piece of frosted or ground glass. Inside the box is an ordinary receptacle for electric lamp.

The wire connections of the engine are shown in Fig. 5, in which "A" is the magnet in valve box; "20" is a battery; "H" is the electric signal light; "22" and "23" are standard relays, and "40" represents the switch box shown in Fig. 7.

10 When the train passes over "5" rail, Fig. 1, the contact shoes form a contact with it. If there be no current in the stop rail, circuit on magnet "A" will be broken when the contact shoes are raised on reaching the high level 15 of the stop rail, and stop is effected. If the block ahead is "clear", current from "5" rail will pass through contact rod, up through relays "22" and "23", and return through other rod to other rail. Relay "23" then 20 closes circuit on magnet and prevents circuit from being broken, and relay "22" closes circuit on signal light, which lights up and shows "clear". As soon as train passes out of block, current will flow back 25 to "6" rail and light signal in engine waiting there.

What I claim as new and desire to secure by Letters Patent is,

1. In a train controlling device, the combination of a track comprising a plurality of successive sections of substantially parallel rails insulated from each other, a track circuit including a resistance and four contact rails for each block; a train stopping 30 means carried by a vehicle upon a track, a "clear" indication light, a closed electric control circuit, an electric magnet for holding inoperative the train stopping means, said magnet included in the said control 35 circuit, a pair of vehicle contacts, two switches included in said control circuit and actuated by the vehicle contacts, a normally deenergized relay including contacts controlling the vehicle control circuit, means 40 45 whereby the normally deenergized relay is energized by the track circuit current when the vehicle contacts engage the contact rails when the block ahead is clear.

Copies of this patent may be obtained for five cents each, by addressing the "Commissioner of Patents, Washington, D. C."

2. In a train controlling device, the combination of a track comprising a plurality 50 of successive sections of substantially parallel rails insulated from each other, two positive and two negative contact rails for each block, a resistance in series with these rails; a train stopping means carried by a vehicle 55 upon a track, an indication light, a closed electric control circuit, an electric control magnet for controlling the train stopping means, said control magnet included in said control circuit, vehicle contact means, two 60 mechanically operated switches connected in the control circuit and actuated by the contact means, an electrically operated switch including contacts controlling the vehicle control circuit and normally separated, a 65 track circuit including a resistance, the contact rails and the transit rails, means for sending the track circuit current through the contact rails to the vehicle contacts to close the contacts of the electrically operated 70 switch controlling the vehicle circuit, when the vehicle contacts engage the contact rails when the block ahead is clear.

3. In a train controlling device, a train stopping means, means for controlling the 75 operation of same, said means comprising a closed electric control circuit carried by a vehicle upon a track, a control magnet included in said control circuit, a pair of mechanically operated circuit breakers for 80 breaking said control circuit, an electrically operated switch adapted when energized to shunt out the contacts of said circuit breakers, the contacts of said electrically operated switch normally separated, a track 85 circuit comprising a resistance, four contact rails and the transit rails connected in series, the current of said track circuit adapted to close the contacts of the electrically operated switch when the vehicle contacts engage the contact rails when the block 90 ahead is clear.

HARRY WISE RICHARDS.
